JOB HUTCHINSON, OF BROOKLYN, NEW YORK.

INTERNAL-COMBUSTION ENGINE.

1,370,542.

Specification of Letters Patent.

Patented Mar. 8, 1921.

Application filed March 22, 1919. Serial No. 284,482.

To all whom it may concern:

Be it known that I, Job Hutchinson, a citizen of the United States, residing at Brooklyn, in the county of Kings and State 5 of New York, have invented new and useful Improvements in Internal-Combustion Engines, of which the following is a specification.

This invention relates to internal combustion engines, and more especially to an improvement in engines of the two cycle type wherein the working cylinder is formed by a sliding sleeve.

To this end the invention has generally 15 in view a special construction whereby the fuel charge may be initially compressed by a novel arrangement of parts to rapidly enter the working cylinder, thereby not only having the advantage of effecting a more 20 complete and expeditious scavenge of the said working cylinder, but at the same time rendering the engine unusually efficient, not only at various speeds, but peculiarly capable of low throttling, an unusual feature 25 in the two cycle motor.

The present invention proposes to provide a novel engine structure wherein the gaseous fuel is initially drawn from the carbureter at atmospheric pressure into a suitable 30 receiving compartment built in the engine, and then drawn into a compression chamber in which it is compressed to about fifteen pounds pressure on the expansion stroke of the sleeve piston, and then permitted to 35 rapidly escape into the working cylinder to again be compressed prior to firing. To increase the working efficiency of the engine, intake and exhaust ports of large capacity are utilized, the former being located at a 40 point relatively remote from the exhaust ports thereby eliminating the necessity of a deflector, while at the same time improving the scavenging action.

As a further object the invention contemplates a special construction designed to secure the greatest possible power coupled with efficiency and simplicity in a standardized form of motor without impairing the 45 strength of parts that should be substantial 50 and durable, and also eliminate vibration without increasing the number of cylinders. In doing this it is proposed to make use of the so-called recoil of the moving parts to perform work instead of being relatively 55 free, which recoil causes the vibration re-

ferred to, thus utilizing the full effect of such explosion.

The present invention provides another feature which is to be found in the fact that this motor is a constant compression motor 60 for the reason that the burned gas displaced is in proportion to the amount of new gas entering the cylinder. Contrasted to this, a four cycle motor always displaces the same amount regardless of the amount drawn in 65 and the compression is therefore affected accordingly. This accounts for the successful low throttling of a four cycle motor, but the constant compression such as provided by the present invention would be better, 70 particularly, if the low throttling can be accomplished. It is to this end, therefore, that the special construction, arrangement of ports, and the priming device of the present invention is directed to the purpose of throwing 75 what new gas is taken in around the spark plugs to improve the ignition and permit low throttling.

Certain mechanical features directed toward securing advantageous results in two 80 cycle motors are described and claimed in co-pending application S. No. 196,822. Additional features are described herein which are related to and are improvements on those of the application No. 196,822. 85

In addition to the above general features, the herein described construction provides a particular type of control means for regulating the supply of fuel to individual cylinders. There is also provided details 90 of a particular relation existing between the size and arrangement of the various intake and exhaust ports and the position of the movable parts with respect to these ports. 95

The above and other objects and features of the invention will be hereinafter more fully explained and claimed in accordance with the illustration in the accompanying drawings, in which:— 100

Figure 1 is an elevation, partly in section of a cylinder embodying the features to be described;

Fig. 2 is a vertical section taken at right angles to Fig. 1;

Fig. 3 is a diagram indicating the relative operative stages of the main piston;

Fig. 4 is a view corresponding to the diagram of Fig. 3, but directed to the stages of operation of the sleeve piston.

110

Fig. 5 is a diagrammatic view illustrating the relative position of the engine parts at the moment of full compression and indicating the 90 degree cycle of compression; 5

Fig. 6 is a diagrammatic view illustrating the relative position of the engine parts at the moment the 90 degree expansion cycle is complete; 10

Fig. 7 illustrates diagrammatically the position of the solid piston and the sleeve piston relative to the exhaust ports at the moment the exhaust ports are wide open, indicating the 120 degree period wide open 15 and the 30 degree opening and the 30 degree closing periods;

Fig. 8 is a diagrammatic view illustrating the relative position of the engine parts at the moment of dead center during the 20 discharge period, and indicating the 100 degree period during which the inlet valves open and close.

Similar reference characters designate 25 corresponding parts throughout the several figures of the drawings.

In carrying the foregoing general features into effect, the same may be effectively combined in various structural embodiments, and by way of illustrating one simple and practical form reference may be had 30 to the accompanying drawings wherein Figs. 1 and 2 show an engine cylinder 1 having a central bore 2 and water jacket 3, and suitably supported on and secured to the 35 crank case 4 by the bolts 5 or their equivalent. As shown, this cylinder is preferably provided at its crank case end with an annular exhaust passage or chamber 6 which 40 communicates with the bore 2 through a series of exhaust ports 7. The outlet from said exhaust passage or chamber 6 is effected through a pair of diametrically opposite discharge ports 8. This type of 45 exhaust provides for quickly releasing the exploded charge and materially assists the scavenging, and consequently prevents choking or back pressures when the engine is running at high speed, thus enhancing the efficiency and flexibility of the engine under 50 all operating conditions.

The upper end 9 of the cylinder may be formed as shown with an upstanding ring or flange 10 for maintaining in place the piston rings of the sliding sleeve piston S 55 which operates within the cylinder. And, to permit the entrance of the compressed fuel charge into the working cylinder of the said sleeve as will hereinafter be more fully explained, this ring is formed with a circular series of intake openings 11 which are thus located relatively remote from the exhaust ports 7, and because of their number and arrangement provide for the rapid and unobstructed entry of the fuel into the 60 said working cylinder.

Between the intake and exhaust ports the cylinder is provided with opposite radially disposed spark plug openings 12 which are threaded in the usual manner to receive the spark plugs P, and terminate at their inner 70 ends in the enlarged sparking pockets or recesses 13 which open into the bore 2 and are covered by the reciprocating compression sleeve S except when the live fuel charge is to be ignited. Thus, the points of 75 the plugs are protected by this sleeve from the usual carbon deposits and are always kept in good sparking condition, and the provision of two plugs in the locations shown insures ample ignition facilities. 80

Referring now more particularly to the sleeve S which reciprocates in the cylinder bore 2, it will be observed that the same is provided at its upper end with a suitable compressor head 14 having a convex inner 85 surface and an annular series of intake ports 15 adapted to register with the openings 11 of the ring 10 at the end of the up-stroke of the sleeve, which is its compression stroke, to permit the compressed 90 fuel charge to enter the working cylinder or explosion chamber C of the sleeve S, while the lower portion is provided with a suitable series of exhaust ports 16 to register with the openings 7 of the exhaust chamber 95 6. The ports 15 are located immediately adjacent the convex inner surface, which latter slopes smoothly into the ports 15. A separate set of compression rings 14^a are provided above and below the intake ports 100 15 in the sleeve to insure efficiency. The relative length and area of the ports 16 as compared to the size of the ports 7 contribute a very important part of the present invention, the details of which will be further explained. The skirt portion S' of the sleeve which extends below the ports 16 has formed therewith, and depending from the lower edge thereof, suitable brackets 17 which hold therein by means of the fastening 18 a wrist pin 19 whose opposite ends pivotally engage with the bifurcated eye portion 20 of the relatively short connecting rods 21 which are two in number and whose lower ends are secured in the usual manner 110 to the crank portions 22 of the shaft 23, while the crank portion 24 of the latter has fitted thereto one end of a long connecting rod 25 which is attached in the usual way to an ordinary piston 26 adapted to freely 115 work within the chamber C of the sleeve S. The structure of the rods 21 is such that with the sleeve S, they counterbalance the weight of the rod 25 and piston 26 thus 120 evenly distributing the weight and maintaining perfect balance while the engine is in operation. This is important in an engine of this character, since when the explosion takes place between the head 14 and piston 26, the rods 21 and 25 are driven in 125 130

opposite directions, and the forces are completely balanced.

The upper end 9 of the cylinder has fitted thereto a novel cylinder head unit for closing the same, and in this embodiment of the invention it preferably assumes the form of a dome whose special features of construction make possible the desirable and necessary compression features heretofore referred to. This cover or dome is designated generally as 27 and may be of the semi-spherical or bee-hive shape shown, and provided with a suitable attaching flange 28 for receiving the fastenings 29 to detachably connect the dome to the cylinder, while the interior thereof has formed integral therewith a partition wall 30 which divides the said interior into an initial fuel receiving chamber 31 and a fuel compression chamber 32. This wall 30 has a valve seat 33 formed therein and opening into the compression chamber 32, and also has formed thereon the bosses 34 for receiving suitable screws or other fastenings 35 to secure a spider 36 in position to slidably guide the stem 37 of a valve V onto and off of its seat 33, and, as shown, a spring 38 confined between the spider and the head of the valve may be utilized to seat the valve under the required conditions.

In connection with this valve V however, it may be noted that the stem 37 thereof is of hollow formation and has its lower end split or cut to form a plurality of yielding clutch fingers 39, while the face of the valve is provided with a closed extension socket 40 which forms a continuation of the hollow bore of the stem and receives the spindle or post 41 carried by the center of the head 14 of the sleeve S. This formation of the valve has in view the retaining of all possible compression in the chamber 32 by providing the closed socket 40, and also the positive unseating of the valve against the tension of the spring 38 on the suction stroke of the sleeve S through the provision of the clutch fingers 39. Thus, it will be apparent that while the suction of the sleeve S tends to unseat the valve V, this action is assisted by the yielding clutch engagement between the valve stem 37 and the post 41, while on the other hand when the sleeve moves up on the compression stroke the spring 38 will initially push the valve to its seat, and the gas compression and continued upward movement of the post 41 will further positively assist this action.

Another novel and important feature of the invention resides in the provision of means for automatically priming the spark plugs P to insure firing at the proper time, and to this end it is proposed to connect the sparking pockets 13 with the fuel compression chamber 32 by means of a novel valved passage. This passage may be of

any desired shape or size, but preferably as shown, consists of the vertical conduit 42 in open communication at one end with a horizontal conduit 43 which leads directly to the pockets 13, while the upper end is in valved communication with an angular passage 44 opening into the floor of the fuel compressor chamber 32. That is to say, the arm of the angular passage 44 which connects with the end of the conduit 42 has a spring pressed ball valve 45 therein which is automatically opened at the compression stroke of the sleeve S to send live fuel to the pockets 13 so that the ignition of the fuel at the end of the compression stroke of the piston 26 within the sleeve is positively insured.

The details of construction which relate most directly to the unusual proportions and arrangements of the intake and exhaust ports and the piston will be understood from the following description. The gas taken into the working cylinder C is only that drawn in by the downward movement of the sleeve piston S and displaced by its upward movement into the initial compression chamber 32. The upward movement of the sleeve piston S compresses the charge until the ports 15 in the sleeve register with the ports 11 in the cylinder extension 10, at which time it enters the working cylinder C and is ready for compression and explosion. The charge after entering the working cylinder C equalizes at atmospheric pressure as the exhaust ports 16 and 7 open their working cylinder to the atmosphere at the time when the inlet ports 15 and 11 open for the gas to enter. Therefore the working cylinder C will have new gas filling the upper half of the space while the lower half yet retains a portion of the exploded gas at atmospheric pressure. It is therefore clear that something should be done in the way of scavenging to expel all of the burned gas or as much of it as possible without losing any of the new gas. The present invention provides for this by arranging the exhaust ports 7 in the cylinder wall 1 to have a fixed opening equal to one-half the stroke of the regular piston 26 and the port 16 in the sleeve S will have ports of $1\frac{1}{2}$ this height or equal to $\frac{3}{4}$ of the stroke of the piston 26.

The two pistons S and 26 when moving toward each other must travel a distance equal to a full stroke of either one during which time the burned gas is being forced out, and when the pistons reach this point the exhaust ports close, leaving some burned gas still in the space which is the explosion or compression space and above which is a full charge of new gas. This space is indicated in the drawing by the space between the dotted lines in the working cylinder C. At this point compression is started and there is a condition existing practically the same

as now exists in the operation of a four-cycle motor with the difference that in the present construction every other stroke of the piston is not wasted.

5 A still further advantage is gained by the fact that the rapidity at which the new gas enters along with some expansion of the new gas after entering the hot chamber C tends toward the expulsion of whatever there is 70 of burned gas remaining in the compression space. This movement provides a much cleaner charge of gas for use when compression begins than is ordinarily found in a four-cycle motor. It has always been a 75 difficult problem to design different sizes of two-cycle motors and determine the proper port opening. This was due to the necessity of using a portion of the cylinder wall which was necessary to the piston travel, 80 and with no other piston or sleeve to assist, the result was either limited port capacity or a loss of gas through the exhaust port and in all cases very low compression. The 85 present design and port arrangement, as shown in Figs. 1 and 2, will apply to any size motor, but for better economy and higher efficiency the exhaust port 16 in sleeve S may be reduced in height depending upon the rapidity and expansion of the 90 new gas. Should the latter expel all of the remaining burned gas from the compression space and reach the exhaust ports 7 before they are closed, then the port 16 may be shortened to prevent a loss of gas. The 95 shortening of these ports 16 will allow further expansion and a lower exhaust pressure, thus making for greater economy. To arrive at this condition by experimentation, the port 16 in the sleeve S are cut considerably lower to begin with and gradually increased to the point where proper scavenging and low exhaust pressure meet, and this can be accomplished without re-designing another motor.

100 45 In order that the explanation just made may be mathematically explainable, it is assumed that there is illustrated an engine, 105 with a bore of four inches and the stroke of four inches. The charge of gas drawn in is approximately 50 cubic inches, or equal to the displacement of the sleeve piston during its stroke of four inches while the volume of the working cylinder is double this amount plus the compression space shown opposite 110 the spark plugs and between the two dotted lines. When the piston 26 and the sleeve head S move toward each other and have reached the dotted lines, the ports 16 of the sleeve S have changed places with the piston 26, the ports 16 having moved down 115 four inches and the piston 26 having moved up four inches, stopping at the lower line where the top edge of the ports 16 are now shown in Fig. 1. The drawings show the 120 piston 26 positioned below the lower edge 125

of the cylinder exhaust ports 7 for a distance of one inch and the upper edge of the sleeve exhaust ports 16 travel past the cylinder exhaust ports 7, also a distance of one inch. The cylinder exhaust ports 7 are two 70 inches high and are located approximately in the middle of the path of travel of the piston 26, and in the lower part of the sleeve and the full port opening is maintained while the piston 26 moves down one inch and up again one inch or 60 degrees before and after dead center, making a full exhaust port opening during 120 degrees of crank motion, while the sleeve S is doing the same, the total port opening being carried through 80 a total crank motion of 240 degrees.

There are shown six sets of these exhaust ports 16 and 7 surrounding the cylinder, each port being one inch in width and two inches in height, making a total of 12 85 square inches in area. The largest valve that can be used in the four-cycle engine without trouble from overheating is about two inches in diameter and with an area of about 3.1 square inches of opening, and the 90 largest overhead valve that can be used in the cylinder of four inches bore is about $1\frac{1}{2}$ inches in diameter and with an area of two square inches. Contrasted to such limitations this engine has exhaust openings six 95 times the size of an overhead valve engine and four times that of the largest valve that can be used successfully in any four-cycle motor because of its peculiar arrangement and size of ports. In addition to the full 100 opening of 120 degrees crank motion, there is in this design a partial additional opening during 60 degrees of crank motion, covering the opening and closing period which adds one-third more to the total opening, 105 making 16 square inches, which is the advantage of this two-cycle engine. The complete port opening period is during 180 degrees of the crank motion of each piston or a total of 360 degrees, and equal to the complete revolution of a single acting four-stroke engine. The compression stroke is ninety degrees of crank motion for each piston, making 180 degrees for a complete stroke, and the same as that of a four-cycle 115 engine. The expansion or explosion stroke covers 90 degrees of crank motion for each piston, making 180 degrees, or 45 degrees more than that of a four-cycle engine, this being for the reason that most four-cycle 120 engines begin to open the exhausts forty-five degrees ahead of lower dead center, giving the latter a $3\frac{1}{2}$ inch working stroke, as compared to the present four inch stroke.

A further advantage which is to be found 125 in the present invention resides in the fact that the first 90 degrees of crank motion following the explosion is of the greatest power value, and this portion of the stroke is doubled, which more than makes up for a 130

slightly lower mean effective pressure, the latter, however, adding to the economy. Comparing this with the existing two-cycle engines of the same bore and stroke, there is gained 25 per cent. in the length of the compression stroke and 25 per cent. in the length of the explosion or expansion stroke, with a port opening five times as great.

Figs. 3 and 4 are diagrams of the four by 10 four engine just described and each of these diagrams indicates what takes place during the revolution of the crank shaft and the complete movement of each piston. When the 12 inch port area is considered and 15 found to be greater than the area of the cylinder diameter it can be easily seen that the exhaust gas pressure will drop to atmospheric pressure as quickly as if the entire cylinder head was suddenly removed. It is 20 recognized that atmospheric pressure in the working cylinder at the time or before the opening of the inlet ports is desirable. The inlet ports 15 and 11 are also one inch in 25 width and are $\frac{3}{4}$ of an inch high, having a total area of $4\frac{1}{2}$ square inches, and are 30 opened and closed during a crank motion of 100 degrees, as shown in the diagram of Fig. 4. With the pressure in the working cylinder C instantly reduced to atmospheric 35 pressure, the inlet ports open and the new charge is transferred by an initial pressure of fifteen pounds above atmospheric pressure and takes its place in the upper end of the sleeve pistons S inside the working cylinder C, and reaching down to the dotted line adjacent the spark plug. This is four 40 inches from the sleeve head and by the time this fresh gas reaches this dotted line it has displaced fifty cubic inches of burned gas. 45 At the beginning of the movement toward each other of the sleeve piston S and the piston 26, the sleeve piston S must move down two inches, carrying the fresh gas with it and continuing to push out burned gas until 50 the fresh gas has reached a point substantially in line with the upper edge of the cylinder exhaust ports. The piston 26 has also moved up two inches, so that the movement of the sleeve piston S and the piston 26 has 55 displaced an additional fifty cubic inches of burned gas or one hundred cubic inches altogether. The piston 26 and the upper edge of the ports in the sleeve S are now in line with the center of the cylinder exhaust ports leaving a space which still contains burned gas which space is equal to the space between the dotted lines. The amount of burned gas thus left in the cylinder may be figured as 60 about twelve cubic inches and at this time it may be compared with the condition of operation of a four cycle motor. In the next movement compression is begun and the fresh gas is compressed into the space between the dotted lines opposite the spark plug. In considering the amount of burned 65

gas possibly remaining in the motor, it is not sufficient to theoretically compute the amount of gas and thus to compare it in operation with that of the four cycle motor for the reason that the speed at which the fresh 70 gas enters the combustion chamber along with the expansion which takes place after entering the hot cylinder will cause considerable swelling and drop below the dotted line, thus displacing still more of the foul 75 gas in the compression space just before it is trapped by the quick closing of the exhaust ports, making a fuller and cleaner charge and providing higher volumetric efficiency than that of the four cycle engine. By this 80 port arrangement there is also secured a substantial supply of water around the head of the piston 26 where the coldest water enters at the inlet W, passing upward and out at a point not shown. 85

The operation of the sleeve piston and the solid piston relative to the positions of the intake and exhaust ports and the peculiar cycles of operation which form an important part of the present invention will be 90 understood readily by reference to the diagrammatic views of Figs. 5-8, inclusive. In Fig. 5, the sleeve piston and the solid piston are shown at the moment of highest compression, that is closest together. The cycle 95 of 90 degrees of the compression period is indicated by the lines and the arrows representing a one-quarter turn of the crank shaft from approximately 270 to 360 degrees. The 100 90 degree cycle of the expansion period is indicated by the lines and the arrows indicating a one-quarter turn of the crank shaft from 0 degrees to 90 degrees. In Fig. 7, the relation of the sleeve piston and the solid piston relative to the exhaust ports is shown 105 as at a point approximately 120 degrees after the position of the parts shown in Fig. 5. The exhaust ports began to open at 90 degrees and continued to open for 30 degrees. A period of full opening extends 110 over a cycle of 120 degrees after which the ports begin to close and complete their closing in a period of 30 degrees additional. Fig. 8 shows the sleeve piston and the solid piston in their extreme remote positions at 115 the moment of dead center and at a time when the intake ports are wide open. This view illustrates how the intake ports begin to open and complete their closing movement in a period of 100 degrees of crank 120 motion, which crank motion is at the middle of the 120 degree period in which the exhaust ports remain fully open.

It will be noted from the drawings and from the dimensions given above for the 125 inlet and exhaust ports and the stroke of each piston, that the inner piston travels down below the lower edge of the exhaust ports; that the exhaust ports are still wide open while the crank shaft approaches, 130

passes over dead center, and leaves dead center; and also that the inlet valves open and close in the period when the exhaust ports are wide open. These features are new in the constructions involved in the present invention and are not used in any of the opposed two cycle motor constructions now known.

In addition to the foregoing the present construction provides for increased economy and efficiency by the use of a particular valve control which makes low throttling possible. Referring to the constructions illustrated in the cylinder heads, Figs. 1 and 2, 46 indicates a stem or shaft extending through the fuel compression chamber 32 and on which is rigidly mounted an eccentric or cam 47, which latter is thrown into engagement with the under surface of the valve V by a lever 48, which may be controlled from a distance. This eccentric is used to prevent or reduce the amount of valve opening. 49 is a compression spring for holding a collar 50 tightly against a packing washer 51. The stem 46 is also packed with a soft packing 52 inside of the packing nut 53, these precautions being taken to maintain compression within the initial compression chamber 32. By use of this valve control one or more cylinders may be cut off for the purpose of cutting down the power on these cylinders and allowing other remaining cylinders to operate at comparatively full load, these latter cylinders thus having sufficient gas to prevent missing and hence operating more efficiently and with better scavenging than if all cylinders were working and the minimum amount of fuel admitted to all. This isolation of cylinders may be done without damage in this type of motor because the balance action of opposed sleeve and piston for each cylinder on the crank shaft gives sufficient flexibility. During ordinary running cylinders may be cut off in turn for the purpose of cooling or locating a damaged spark plug, thus saving the gas which in present day motors is passed through the cylinder and into the muffler there often causing explosion.

From the foregoing it will be apparent that the novel dome construction provides for first drawing the live fuel from the carburetor into the initial fuel receiving chamber 31 at atmospheric pressure, due to the fact that as the sleeve S descends in the cylinder a vacuum is created in the chamber 32, and the valve V is opened by this vacuum and, the assistance of the clutch engagement between the post 41 and valve stem, whereby the fuel at low pressure is also drawn from 31 into 32 until the end of the suction stroke of the sleeve. Then the upward movement of the sleeve S causes the closing of valve V, and the compression of the gas in chamber 32 until the head 14 of

the sleeve registers with the intake ports 11 when the fuel will expand into the chamber C of the sleeve and effect the scavenging of the exploded gases through the exhaust ports 16-7, since the head of the piston 26 permits this as shown in Fig. 2. After the fresh charge is in the chamber C the sleeve S descends and the piston 26 rises, and when the ports 15 of the sleeve register with the pockets 13, which are primed with fresh gas on the compression stroke, the plugs P ignite the fuel charge compressed and caged between the head 14 and piston 26 to cause the working stroke which sends the elements S and 26 in opposite directions to perform their proper functions. These operations are repeated during each cycle, and accurately carry out all of the designed and intended operations with precision and efficiency.

In addition to the points of advantage hereinbefore indicated, it will be noted that this construction makes it possible to begin the exhaust port opening opposite the center of the cylinder exhaust ports and to widen this opening equally in both directions.

I claim:

1. An internal combustion engine including a cylinder having a plurality of fuel intake ports and an annular exhaust chamber communicating with said cylinder bore through a plurality of discharge ports in said cylinder wall, a fuel receiving chamber in communication with said plurality of fuel intake ports, a fuel compression chamber, a sleeve slidably mounted in the cylinder and having a plurality of fuel intake ports to receive fuel from the compression chamber, and also having a series of exhaust openings to communicate with the annular exhaust chamber through the exhaust openings in said cylinder wall, said exhaust openings in said sleeve being at least one and one half times the length of said exhaust openings in said cylinder walls to prolong the period of full opening of the latter.

2. An internal combustion engine including a cylinder having a plurality of fuel intake ports and an annular exhaust chamber having a plurality of discharge ports formed in said cylinder wall, a fuel receiving chamber in communication with said plurality of fuel intake ports, a fuel compression chamber, a sleeve slidably mounted in the cylinder and having a plurality of fuel intake ports to receive fuel from the compression chamber, and also having a series of exhaust openings to communicate with the annular exhaust chamber through said openings in said cylinder wall, said exhaust openings in said sleeve having at least one and one half times the area of said exhaust openings in said cylinder.

3. An internal combustion engine including a cylinder having exhaust ports in said

- cylinder wall, a fuel supply dome formed with separate fuel receiving and compression chambers, an automatic valve between the same, a compression sleeve within the cylinder and having ports for communicating with the compression chamber and other ports in said cylinder wall communicating with said exhaust ports, and a piston working in said sleeve, the exhaust ports 5 in said sleeve being so located with respect to said piston that when said piston and sleeve are moved in opposite directions the piston begins to uncover said ports when the latter are directly opposite the exhaust ports 10 in said cylinder.
4. An internal combustion engine including a cylinder having exhaust ports in the wall thereof, a fuel supply dome formed with separate fuel receiving and compression chambers, an automatic valve between the same, a compression sleeve within the cylinder and having ports for communicating with the compression chamber and other 15 ports communicating with said exhaust ports in said cylinder wall, and a piston working in said sleeve, the ports in said sleeve being so located with respect to said piston that when said piston and sleeve are moved in opposite directions the piston begins to uncover said ports when the latter are directly opposite the center of said exhaust ports in said cylinder.
5. An internal combustion engine including a cylinder having a series of exhaust ports extending therearound in the wall thereof, a piston sleeve within said cylinder having a series of exhaust ports corresponding to and arranged to register with said cylinder exhaust ports, and an annular exhaust chamber surrounding said annular series of cylinder exhaust ports and adapted to receive the exhaust in all directions and maintain equal expansion and contraction of the cylinder and avoid distortion, the length 20 of said exhaust ports in said sleeve being at least one and one half times as great as the length of said cylinder exhaust port to prolong the period of full opening of the latter.
6. An internal combustion engine including a cylinder having a series of exhaust ports extending therearound in the wall thereof, a piston sleeve within said cylinder having a series of exhaust ports corresponding to and arranged to register with said cylinder exhaust ports, and an annular exhaust chamber surrounding said series of cylinder exhaust ports to receive the exhaust in all directions therefrom and having outlet 25 passages at opposite points in said chamber to equalize the exhaust from and the temperature of said chamber parts, the length of said exhaust ports in said sleeve being at least one and one half times as great as the length of cylinder exhaust port 30 to prolong the period of full opening of the latter.
7. An internal combustion engine including a cylinder having a plurality of fuel intake ports and an annular exhaust chamber having a plurality of discharge ports, a fuel receiving chamber in communication with said plurality of fuel intake ports, a fuel compression chamber, a sleeve slidably mounted in the cylinder and having a plurality of fuel intake ports to receive fuel from the compression chamber, and also having a series of exhaust openings to communicate with the annular exhaust chamber, said exhaust openings in said sleeve being at least one and one half times the length of said annular exhaust chamber, the ends of said sleeve exhaust ports farthest removed from said sleeve intake ports being directly opposite to the corresponding end of said cylinder exhaust ports when said intake ports of said sleeve and cylinder are in registry. 35
8. An internal combustion engine including a cylinder having a series of exhaust ports extending therearound, a piston sleeve within said cylinder having a series of exhaust ports corresponding to and arranged to register with said cylinder exhaust ports, and an annular exhaust chamber surrounding said series of cylinder exhaust ports and adapted to receive the exhaust in all directions and maintain equal expansion and contraction of the cylinder and avoid distortion, the length of said exhaust ports in said sleeve being at least one and one half times as great as the length of said cylinder exhaust ports, the ends of said sleeve exhaust ports farthest removed from said sleeve intake ports being directly opposite to the corresponding end of said cylinder exhaust ports when said intake ports of said sleeve and cylinder are in registry. 40
9. An internal combustion engine including a cylinder having a series of exhaust ports extending therearound and in the wall thereof, a piston sleeve having a head portion in said cylinder and having a series of exhaust ports corresponding to and arranged to register with said cylinder exhaust ports, and a piston adapted to move within said sleeve, the ends of said sleeve exhaust ports farthest from said sleeve intake ports being directly opposite to the corresponding ends of said cylinder exhaust ports when said sleeve head and said piston are in the extreme removed positions, and said piston being as far beyond the nearest edge of said sleeve exhaust ports as the far edge of said sleeve exhaust ports are beyond the far edge of said cylinder exhaust ports. 45
10. A two cycle internal combustion engine including a cylinder having fuel intake and exhaust ports, a compression sleeve mounted for movement within said cylinder 50

and having an explosion chamber and intake and exhaust ports adapted to register respectively with said intake and exhaust ports of said cylinder, and a piston adapted 5 to move within said sleeve, said sleeve exhaust ports being of such size with respect to said cylinder exhaust ports as to register with and maintain said cylinder exhaust ports fully open during the entire period 10 during which the inlet ports of said cylinder and said sleeve begin to register on opening and move apart when closing.

11. A two cycle internal combustion engine including a cylinder having fuel intake and exhaust ports, a compression sleeve mounted for movement within said cylinder and having an explosion chamber and intake and exhaust ports adapted to register respectively with said intake and exhaust 15 ports of said cylinder, a piston adapted to move within said sleeve, a common crank shaft for operating said sleeve and said piston, said sleeve exhaust ports being so arranged that they begin to open before the 20 inlet ports open by an initial lead of 40 degrees of motion of said crank shaft and they remain open during 40 degrees of crank shaft movement after said inlet ports close.

30 12. A two cycle internal combustion engine including a cylinder having fuel intake and exhaust ports, a compression sleeve mounted for movement within said cylinder and having an explosion chamber and intake and exhaust ports adapted to register respectively with said intake and exhaust 35 ports of said cylinder, a piston adapted to move within said sleeve, a common crank shaft for operating said sleeve and said piston, said sleeve exhaust ports being so arranged as to remain completely open during 40 20 degrees of movement of said crank shaft before said inlet ports begin initial register, and remain completely open after said inlet 45 ports have closed and ceased to register.

13. An internal combustion engine including a cylinder having a fuel intake port and also having an initial fuel receiving chamber and a fuel compression chamber directly adjacent each other and a communicating port, a sleeve slidably mounted in said cylinder and having an explosion chamber therein and control means for positively controlling the communication between the fuel receiving chamber and the fuel compression chamber, and supplemental control means mounted on said engine and independent of said first control means for regulating the degree of opening of said 50 communicating port.

60 14. An internal combustion engine including a cylinder having a fuel intake port and also having an initial fuel receiving chamber and a fuel compression chamber directly

adjacent each other and a communicating 65 port, a sleeve slidably mounted in said cylinder and having an explosion chamber therein and control means for positively controlling the communication between the fuel receiving chamber and the fuel compression chamber, and adjustable control 70 means for regulating the degree of movement of a valve in said communicating port.

15. An internal combustion engine including a cylinder having intake and exhaust 75 ports, and also having an initial fuel receiving chamber and a compression chamber formed directly adjacent each other within the engine structure, an automatic valve adapted to establish communication between 80 said fuel receiving and compression chambers, adjustable control means for regulating the degree of movement of said automatic valve, a compression sleeve within the cylinder and having an explosion chamber therein and ports for communication with the compression chamber and other ports communicating with said exhaust ports, and a 85 piston working in said sleeve.

16. An internal combustion engine including a cylinder having exhaust ports adjacent the crank case, and a fuel supply dome detachably fitted to the other end, said dome having an interior wall dividing the same 90 into fuel receiving and compression chambers and provided with a valve seat opening into the latter chamber, a spring pressed valve located wholly within the compression chamber and normally held against said seat, adjustable control means for regulating the 95 degree of movement of said valve, a compression sleeve having intake ports adapted to communicate with the compression chamber and exhaust ports adapted to register with corresponding cylinder ports, and a 100 piston working in said sleeve.

17. An internal combustion engine including a cylinder having exhaust ports, a fuel supply dome mounted on the upper end of the cylinder jacket and having an interior partition dividing the same into a relatively small fuel receiving chamber and a relatively capacious fuel compression chamber and provided with a valve opening, a spider fitted to the partition, a valve having a stem extending into the compression chamber and guided in said spider, a spring confined between the spider and the valve for maintaining the same normally seated, adjustable control means for regulating the 110 degree of movement of said valve, a compression sleeve having intake and exhaust ports for respectively communicating with the compression chamber and cylinder exhaust port, and a piston working in said 115 sleeve.

18. An internal combustion engine including a cylinder having a fuel intake port and

also having an initial fuel receiving chamber and a fuel compression chamber directly adjacent each other and a communicating port, a sleeve slidably mounted in said cylinder and having control means for positively controlling the communication between the fuel receiving chamber and the fuel compression chamber, a valve in said communicating port and operating in conjunction with said control means, and adjustable control means for regulating the degree of opening of said valve comprising a shaft extending from the exterior of said dome into the interior thereof and journaled therein, 10 cam means mounted on said shaft and adapted to limit the movement of said valve, and a lever connected to the exterior end of said shaft.

19. An internal combustion engine including a cylinder, a fuel supply dome fitted thereto and having a partition wall dividing the same into separate receiving and compression chambers, and also having a valve seat, a valve guide fitted to said wall, a valve including a head portion provided with a closed socket extending to one side thereof and projecting into the fuel receiving chamber while the other side carries a hollow stem split at its free end to provide a plurality of yielding clutch fingers, a spring confined between the guide and the head of the valve, a slidable compression sleeve, means carried by the latter and engaged by the valve stem, a shaft extending into said dome and journaled in the walls thereof, cam means mounted on said shaft and arranged to engage said valve to limit the opening movement thereof, and means outside of said engine for actuating said shaft.

20. An internal combustion engine of the two cycle type including a cylinder having a series of fuel intake and a series of exhaust ports extending therearound, a compression sleeve mounted for movement in said cylinder and having a head, an explosion chamber, intake and exhaust ports adapted to register respectively with said cylinder intake and exhaust ports, a piston adapted to move within said sleeve, the exhaust ports of said sleeve being at least twice the length of the intake ports of said sleeve.

21. An internal combustion engine of the two cycle type including a cylinder having a series of fuel intake and a series of exhaust ports extending therearound, a compression sleeve mounted for movement in said cylinder and having a head, an explosion chamber, intake and exhaust ports adapted to register respectively with said cylinder intake and exhaust ports, a piston adapted to move within said sleeve, the exhaust ports of said sleeve having an area at least twice that of the area of the intake ports of said sleeve.

22. An internal combustion engine of the two cycle type including a cylinder having a series of fuel intake and a series of exhaust ports extending therearound, a compression sleeve mounted for movement in said cylinder and having a head, an explosion chamber, intake and exhaust ports adapted to register respectively with said cylinder intake and exhaust ports, a piston adapted to move within said sleeve, the area of said cylinder exhaust ports being greater than the area of the bore of said cylinder.

23. An internal combustion engine of the two cycle type including a cylinder having fuel intake and exhaust ports, a compression sleeve mounted for movement within said cylinder and having an explosion chamber and intake and exhaust ports adapted to register respectively with said intake and exhaust ports of said cylinder, a piston adapted to move within said sleeve, a common crank shaft for operating said sleeve and said piston, said exhaust ports being so arranged as to be open during 180 degrees of revolution of said crank shaft.

24. An internal combustion engine including a cylinder having fuel intake and exhaust ports, a compression sleeve mounted for movement within said cylinder and having an explosion chamber and intake and exhaust ports adapted to register respectively with said intake and exhaust ports of said cylinder, a piston adapted to move within said sleeve, a common crank shaft for operating said sleeve and said piston, said exhaust ports in said cylinder being greater in area than the area of said piston head and being arranged to remain open during 180 degrees of revolution of said crank shaft.

25. An internal combustion engine including a cylinder having a series of fuel intake and a series of exhaust ports extending therearound, a compression sleeve mounted for movement in said cylinder and having a head, an explosion chamber, intake and exhaust ports adapted to register respectively with said cylinder intake and exhaust ports, a piston adapted to move within said sleeve, said piston being arranged to travel at least one quarter of its stroke below the edge of said exhaust ports in said sleeve and said cylinder while the latter are in registry.

26. An internal combustion engine including a cylinder having intake and exhaust ports, and also having an initial fuel receiving chamber and a compression chamber formed directly adjacent each other within the engine structure, a valve adapted to establish communication between said fuel receiving and compression chambers, a compression sleeve within the cylinder and having an explosive chamber therein and intake ports for communication with the compression chamber and other ports com-

- municating with said exhaust ports, and a piston working in said sleeve, said intake ports in said sleeve having an area at least fifty per cent. greater than the area of opening of said valve.
27. An internal combustion engine including a cylinder having fuel intake and exhaust ports, a compression sleeve mounted for movement within said cylinder and having an explosion chamber and intake and exhaust ports adapted to register respectively with said intake and exhaust ports of said cylinder, a piston adapted to move within said sleeve, and a common crank shaft for operating said sleeve and said piston, said sleeve exhaust ports being so arranged as to leave said cylinder exhaust ports completely open during a period of 60 degrees of revolution of said crank shaft while the crank shaft approaches dead center and for a period of 60 degrees of revolution of said crank shaft after the crank shaft starts upward from dead center.
28. An internal combustion engine including a cylinder having fuel intake and exhaust ports, a compression sleeve mounted for movement within said cylinder and having an explosion chamber and intake and exhaust ports adapted to register respectively with said intake and exhaust ports of said cylinder, a piston adapted to move within said sleeve to uncover said sleeve exhaust ports and to move downward beyond the lower edge of said exhaust ports, and a common crank shaft for operating said sleeve and said piston, said sleeve exhaust port being so arranged as to leave said cylinder exhaust ports completely open during a period of 60 degrees of revolution of said crank shaft while the crank shaft approaches dead center, and for a period of 60 degrees of revolution of said crank shaft after the latter starts away from dead center.
29. An internal combustion engine including a cylinder having fuel intake and exhaust ports, a compression sleeve mounted for movement within said cylinder and having an explosion chamber and intake and exhaust ports adapted to register respectively with said intake and exhaust ports of said cylinder, a piston adapted to move within said sleeve, and a crank shaft for operating said sleeve and said piston, said sleeve exhaust ports being longer than said cylinder exhaust ports, and said sleeve inlet ports being arranged to complete the opening and closing movement during the period while said exhaust ports of said cylinders are wide open.
30. In an internal combustion engine of the two cycle type, a cylinder having a series of intake and a series of exhaust ports in the wall thereof, and a sleeve piston in said cylinder having an explosion chamber therein and a series of intakes and a series of ex-
- haust ports in the wall of said sleeve piston adapted to be moved with said sleeve piston over and to uncover said ports in said cylinder wall, said exhaust ports in said sleeve being longer than the exhaust ports in said cylinder in order to prolong the period of full opening of the latter, and said inlet ports in said sleeve being adapted to be moved into registry with said inlet ports in said cylinder and to open and close the same while said cylinder exhaust ports are full open.
31. In a two cycle engine, a cylinder having intake ports and exhaust ports in the wall thereof, a sleeve piston within said cylinder and having an explosion chamber within said sleeve piston and having a plurality of exhaust ports adapted to be moved with said sleeve into position over said exhaust ports in said cylinder wall, a second piston within said sleeve piston, and a common crank shaft for said sleeve piston and said second piston, the exhaust valves in said cylinder and in said sleeve piston being so positioned that the impulse cycle includes an impulse relative movement of the sleeve piston and second piston approximately equal to that of the exhaust movement of the sleeve piston and second piston.
32. In a two cycle internal combustion engine, a cylinder having intake ports and a plurality of long narrow exhaust ports in the wall thereof, a sleeve piston within said cylinder and having an explosion chamber within said sleeve piston and having a plurality of long narrow exhaust ports adapted to be moved into position over said exhaust ports in said cylinder wall, a second piston within said sleeve piston and adapted to move over and beyond said exhaust ports in its travels, and a common crank shaft for said sleeve piston and said second piston, said exhaust ports in said sleeve piston and said exhaust ports in said cylinder wall being so located that the impulse cycle includes an impulse relative movement of the sleeve piston and second piston approximately equal to that of the exhaust movement of the sleeve piston and second piston.
33. An internal combustion engine including a cylinder having a plurality of fuel intake ports and an annular exhaust chamber having a plurality of discharge ports leading thereto from the bore of said cylinder, and a sleeve slidably mounted in said cylinder and having a series of exhaust openings to communicate with the openings in said cylinder wall leading to said exhaust chamber, said exhaust openings in said sleeve being at least one and one-half times the length of the openings in said cylinder wall leading to said annular chamber, the ends of said sleeve exhaust ports farthest removed from said sleeve intake ports being directly opposite to the corresponding end of

said cylinder discharge ports when said intake ports of said sleeve and cylinder are in registry.

34. In a two cycle internal combustion engine, a cylinder having intake ports and a plurality of long narrow exhaust ports in the wall thereof, a sleeve piston within said cylinder and having an explosion chamber within said sleeve piston and having a plurality of long narrow exhaust ports adapted to be moved into position over said exhaust ports in said cylinder wall, a second piston within said sleeve piston and adapted to move over and beyond said exhaust ports in its travel, and a common crank shaft for said sleeve piston and said second piston, said exhaust ports in said sleeve piston and said exhaust ports in said cylinder wall being so located that the movement of said sleeve piston and said second piston begins to open the exhaust ports at a point about 90 degrees of the cycle of revolution of said crank shaft.
35. In a two cycle internal combustion en-

gine, a cylinder having intake ports and a plurality of long narrow exhaust ports in the wall thereof, a sleeve piston within said cylinder and having an explosion chamber within said sleeve piston and having a plurality of long narrow exhaust ports adapted to be moved into position over said exhaust ports in said cylinder wall, a second piston within said sleeve piston and adapted to move over and beyond said exhaust ports in its travel, and a common crank shaft for said sleeve piston and said second piston, said exhaust ports in said sleeve piston and said exhaust ports in said cylinder wall being so located that the movement of said sleeve piston and said second piston begins to open the exhaust ports at a point about 90 degrees of the cycle of revolution of said crank shaft.

In testimony whereof I have hereunto set my hand.

JOB HUTCHINSON.
